UNITED STATES PATENT OFFICE.

HARVEY V. HIGLEY, OF DETROIT, MICHIGAN, ASSIGNEE, BY MESNE ASSIGNMENTS, TO
THE ISKO COMPANY, OF CHICAGO, ILLINOIS, A CORPORATION OF DELAWARE.

GAS-MEASURING APPARATUS.

1,275,255.

Specification of Letters Patent. Patented Aug. 13, 1918.

Application filed May 7, 1918. Serial No. 233,049.

To all whom it may concern:

Be it known that I, HARVEY V. HIGLEY, a citizen of the United States, and resident of Detroit, Wayne county, State of Michigan, have invented certain new and useful improvements in Gas-Measuring Apparatus, of which the following is a specification.

The present invention relates to gas measuring apparatus and more particularly to an apparatus for accurately measuring out volumes of a gas. The apparatus has been devised particularly for measuring volumes of sulfur dioxide to be tested for purity and moisture content, although, as will be apparent it is not limited to this use.

The principal features of the invention consist in the provision of means for delivering volumes of gas which have been measured with extreme accuracy; in the provision of means closely adjacent the measuring means for determining the temperature and pressure of the gas; in the provision of an apparatus which is free from pockets which might interfere with accuracy of the measuring; in the provision of an apparatus of the type mentioned constructed and arranged to deliver all the gas measured and in the provision of an apparatus which is easily manipulated. Other features and objects will be apparent from the description taken in connection with the drawings in which:

Figure 1 is a front elevation of an apparatus constructed in accordance with the present invention;

Fig. 2 is a vertical transverse section taken substantially on the line 2—2 of Fig. 1, the tubular parts attached to the front thereof being omitted; and

Fig. 3 is a sectional view illustrating a detail taken substantially on the line 3—3 of Fig. 1.

Referring to the drawings it will be seen that the apparatus comprises a vertical rectangular backing board 10 supported by the foot pieces 11 and pivotally carrying, as by means of the bolt 12, a front rectangular board 13 which is of smaller size than the backing board 10. As shown, the board 13 is spaced from the board 10 and is so held by means of the spacing sleeve 14 around the bolt 12 and the blocks 15 secured to the

back board 10 adjacent three of the corners of the front board. At the other corner, the upper right hand corner of Fig. 1, the front board has a pin 16 which is adapted to engage in any one of the three recesses 17 formed in the back board. As shown the front board carries a spacing sleeve 18 which slides on the wear plate 19 carried by the back board, and a spring 20 within the sleeve acts against a collar 21 secured to the pin 16 to force the latter into one of the recesses. It will be seen that the recesses 17 are arranged so that when the pin 16 is in the central one the front board is horizontal and when in either one of the end recesses 17 the said board is tilted to the left or the right according to which hole the pin engages.

The parts of the apparatus which are used for measuring the gas are secured in any suitable manner to the front side of the board 13. As shown they comprise a substantially cylindrical gas holder or measuring vessel 22 having conical ends 23 and 24, the latter being reduced down to form the tubular extension 25 provided with a stop cock 26, this portion 25 being connected by means of a rubber tube 27 to a vessel 28 containing a liquid such as mercury. It is necessary to raise and lower the vessel 28 and for this purpose any suitable supporting means may be provided. As shown, the vessel rests in a ring 29 slidably supported on a vertical bar 30 secured to the back board. A thumb screw 31 is provided to lock the ring 29 to the bar 30 in any desired vertical adjustment.

The upper conical end 23 of the gas holder 22 is reduced down to form the tube 32 having a stop cock 32' and constitutes the stem of a T. At the left of the stem the horizontal portion of the T is provided with a stop cock 33 and immediately at the right with a stop cock 34. To the left of the stop cock 33 the tube extends horizontally to a ground glass coupling connection 35 which joins the tube 36 to a tube 37 in the form of an inverted U this being provided for the purpose of preventing mercury from passing out through the end of the tube 37 in case the mercury is allowed to flow past the stop cock 33. At the right of the stop cock 34 is a T 38 connected by a ground glass coupling

39 to the section 40 of tubing just at the right of the stop cock 34. The stem 41 of the T 38 has a stop cock 42 and the lower end thereof is open to the atmosphere. The right hand end of the T 38 is joined to the body of a stop cock 43 and just above the said T is a horizontal section of tubing 44 also joined to the body of the cock 43. The section 44 is connected to a horizontal length 10 45 of tubing by means of the vertical piece 46, the left hand end of section 45 extending over the edge of the front board. At the right the body of the cock 43 is connected to a T section 47 of tubing by means of another 15 ground glass coupling connection 48. The plug 49 of the stop cock 43 is formed with the two substantially parallel inclined passages 50 and 51, the former of which is adapted to connect the tube 33 to the tube 52 20 and the latter to connect the tube 44 to the tube 52, the arrangement being such that when one connection is made the other is cut off.

The stem 53 of the T 47 is connected to a 25 vertical tube 54 by means of a ground glass coupling connection 55 and this tube 54 has a stop cock 56, its lower end being enlarged to form a spherical vessel 57. An inclined tube 58 is connected to the lower end of the 30 vessel 57 and at its upper end is connected to a spherical vessel 59 similar to the vessel 57 excepting that it has the mouth 60 open to the atmosphere. A scale 61 is carried by the board 13 in rear of the tube 58, this scale 35 being graduated preferably in metric units. The vessel 57 contains mercury and together with the parts last described forms a manometer for indicating the pressure of the gas in the apparatus.

The right hand end of the T 47 is joined to a vertical tube 62 which extends downward nearly to the lower edge of the board 13 where it is connected to the horizontal tube 63 extending the entire length of the board 45 13. Just to the left of where the tube 62 joins the tube 63 is a stop cock 64 and the right hand end of the tube 63 is adapted to be connected to a source of gas supply 65 by means such as a tube 66, a valve 67 and pressure indicator 68 being provided as shown.

In order to know the temperature of the gas which is drawn to the measuring vessel 22, a thermometer 70 may be secured to the board 13 adjacent said vessel. All the parts 50 just described excepting the flexible tubes are preferably constructed of glass.

Before using the apparatus the volume from the cock 26 to the cocks 33 and 34 including the measuring vessel 22 is accurately 55 determined. In the operation of the device the gas holder 22 is repeatedly filled with the gas to be tested, its pressure being accurately determined by the manometer 58 and its temperature by the thermometer 70. The 60 volume of gas is then corrected to the stand-

ard conditions of zero degrees centigrade and 760 mm. pressure, under which conditions the weight of a liter of the gas is known. This measured volume of what is now a known weight of gas is forced out of 70 the gas holder 22 by raising the vessel 28, the gas being discharged at the end 69 of the tube 37.

In using the apparatus the first step is to 75 drive out the air. For this purpose the valve to the gas supply 67 and cocks 26, 42, 33 and 56 are closed, while the cocks 32, 34 and 64 are open and the cock 43 turned to connect the tubes 33 and 52. The front board is now 80 turned counterclockwise so that the spring pressed pin 16 engages the upper hole 17 and the vessel 28 containing mercury is raised to the position illustrated in Fig. 1. The cock 26 is now opened about one-half way whereupon the mercury passes through 85 the same and rises in the gas holder 22 past the cock 32 to the horizontal stretch of tubing, flowing to the left to the closed cock 33 and to the right as far as the stop cock 43 which is now closed. After this the cock 26 90 is closed and the front board returned to horizontal position. The gas valve 67 is now opened and the gas allowed to pass with considerable velocity out through the tube 63, thus ridding this tube of any air. The gas valve 67 and cock 64 are now closed and the cock 43 turned so as to connect the tubes 44 and 52. Thereupon the gas valve 67 is again opened permitting gas to flow through the vertical tube 62, the horizontal tube 45 100 47 through the cock 43 to the sections 44, 46 and 48, thereby ridding all these sections of air. The gas valve 67 and cock 43 are now closed.

The apparatus is now in condition to have 105 a supply of gas drawn into the gas holder 22. For this purpose the vessel 28 containing the mercury is lowered to a position indicated by the dotted line $a-a$, Fig. 1, the cock 43 is turned to connect the tubes 52 and 33 and the cock 34 is opened. The gas 110 valve 67 is now opened until a pressure of about 3 or 4 cm. of mercury is registered on the pressure indicator 68. Thereupon the stop cock 26 is partially opened permitting the mercury to recede from the cock 115 43 leaving the stem 41 filled. In order that the mercury in the horizontal tube just to the left of the stem 32 shall flow back, the board is swung so that the locking pin engages the lower recess 17. On account of 120 this inclination of the board the tube to the left of the stem 32 will be drained of mercury and as the level falls in the gas holder 22, of course gas will be drawn into the latter. The board is now turned to its horizontal position. It is desirable to maintain 125 the pressure of the gas substantially constant at about 3 mm. of mercury, and for this purpose the gas valve 67 may be opened occasionally and when the mercury reaches 130

the stop cock 26 the latter is closed and also the gas valve 67. The next step consists in obtaining the pressure of the gas in the holder 22. For this purpose the cock 64 is opened until the pressure of gas in the tube 62 is reduced to about one-half a centimeter of mercury, then it is closed and the cock 56 opened which permits the pressure in the gas holder 22 to be determined by the manometer 58. It is best to have this pressure reading at a constant figure if possible and this may be accomplished by allowing gas to escape at the cock 64. The temperature as indicated by the thermometer 70, the 10 barometric pressure, and the difference of the pressure readings on the scale 61 are now recorded.

In order to expel the gas from the holder 22, the cocks 34 and 26 are closed and the 15 mercury supply 28 is raised to its upper position. The cock 33 is opened and the board is turned clockwise so that the pin engages the lower recess 17. The cock 26 is now opened so that mercury fills the holder 22 and forces gas out of the discharge end 69. When the mercury reaches the T at 32 it first fills to the right up to the cock 34 and then to the left cock 33. As the tube is somewhat inclined it is easy to determine 20 when the mercury reaches this latter cock so that it may be closed at the proper time. This completes the measuring of one volume of the gas. In repeating, since all the tubes are filled with gas, the operation is simpler as the steps of driving out the air are omitted. For measuring another volume of gas the mercury supply 28 is lowered to the position *a*—*a*, cock 34 is opened and the gas valve 67, to admit gas to build 25 up a pressure of about 3 millimeters of mercury, then the cock 26 is opened so that a volume of gas will be drawn into the gas holder 22 as the mercury flows out of the same. The subsequent steps are the same as 30 already described for expelling the charge of gas.

When the last volume of gas has been discharged from the gas holder it is necessary to drive out the gas which remains in the 35 tube 37 at the left of the cock 33, as when another gas, or gas of the same kind but from a different supply is being measured for the purpose of having it analyzed, this small quantity of gas in the tube 37 would be forced over to the analyzing apparatus which of course would interfere with the accurate analysis of the desired gas. For the purpose of forcing out the gas left in the tube 37 the cock 33 is closed, the cock 34 is opened, and the cock 43 turned to connect the tubes 52 and 38. Cock 67 is closed and 40 open as outlet for gas forced out of 38. The board 13 is turned counter-clockwise so that spring pressed pin 16 engages the upper hole 17. Then with the mer-

cury supply 28 in its upper position the mercury will flow up to the cock 43 which is then closed. Thereafter the mercury supply is lowered and the cocks 42 and 26 opened, a small dish is placed under the open end of 45 the stem 41 to collect the small amount of mercury which was in the said stem, this mercury being returned to the reservoir 28. As the mercury supply 28 is now at the lower level it will flow out of the tube 38. When it reaches the stem 32, the board is turned clockwise until the pin 16 engages the lowest hole 17. The air drawn in through the cock 42 will fill the gas holder 22, then the cock 34 is closed and the cock 33 opened, the vessel 28 raised, thereby driving out the air from the holder 22 and expelling the gas from the tube 37. This 50 operation repeated three or four times will rid the tubing of any of the gas.

From the foregoing description it will be seen that an arrangement of parts is provided which forms an exceedingly efficient apparatus and one which can be manipulated easily, quickly, and with a minimum effort. Furthermore, the feature of mounting the parts on a pivoted board aids in draining the liquid from the horizontal tube 38 and also makes it easy to determine when the liquid reaches the stop cock 43 in flowing 55 into the section 38 of the tubing. The provision of the ground glass coupling connections permits sections of the tube to be removed for repairs without disturbing the other parts of the apparatus.

Having thus described the invention what is claimed as new and desired to be secured by Letters Patent is:

1. A gas measuring apparatus including in combination, a vertical measuring vessel, a horizontal T having its stem connected to the top of the vessel, a stop cock at the bottom of the vessel, a stop cock in each of the horizontal legs of the T, one leg having connections to a gas supply and the other leg connected to a discharge tube, all of the above mentioned parts being mounted on a support pivoted for swinging movement about a horizontal axis, a vertically adjustable liquid reservoir, and a flexible tube connecting the reservoir to the bottom of said vessel below the stop cock.

2. A gas measuring apparatus including in combination, a vertical measuring vessel, a horizontal T having its stem connected to the top of the vessel, a stop cock at the bottom of the vessel, a stop cock in each of the horizontal legs of the T, one leg having connections to a gas supply and the other leg connected to a discharge tube, all of the above mentioned parts being mounted on a support pivoted for swinging movement about a horizontal axis, a vertically adjustable liquid reservoir, a flexible tube connecting the reservoir to the bottom of said

- vessel below the stop cock, and means for locking said support in any one of a plurality of angular positions on its pivot.
3. A gas measuring apparatus including in combination, a vertical measuring vessel, a horizontal T having its stem connected to the top of the vessel, one leg of the T having connections to a gas supply, the other leg joining a discharge tube having an inverted U portion, a vertically adjustable liquid reservoir, a flexible tube joining said reservoir to the bottom of the vessel, and a stop cock at the bottom of the vessel and in each of the two legs of the said T.
- 15 4. A gas measuring apparatus including in combination, a vertical measuring vessel, a horizontal T having its stem connected to the top of the vessel, one leg of the T having connections to a gas supply, the other leg joining a discharge tube, a front board carrying the above mentioned parts, a back board having a pivot supporting said front board, means on one board co-operating with the other to lock the front board in any one of a plurality of angular positions on its pivot, a liquid reservoir, a flexible tube connecting said reservoir to the bottom of the vessel, a stop cock at the bottom of the vessel and in each of the said legs, and means for supporting said reservoir on the back board for adjustment vertically.
5. A gas measuring apparatus including in combination, a horizontal tube having two downwardly extending stems, a tube adapted to be connected to a gas supply, a stop cock adapted to connect said two tubes or put the second mentioned tube in communication with the atmosphere, a stop cock in the stem nearest the first mentioned cock, the lower end of this stem being open to atmosphere, a measuring vessel having its top connected to the other stem, a stop cock in said first mentioned tube at each side of the stem connected to the vessel, a vertically adjustable liquid reservoir, a flexible tube connecting the reservoir to a stem at the bottom of the vessel, and a stop cock in the last mentioned stem.
- 50 6. A gas measuring apparatus including in combination, a horizontal tube having two downwardly extending stems, a tube adapted to be connected to a gas supply, a stop cock adapted to connect said two tubes or put the second mentioned tube in communication with the atmosphere, a pressure indicator connected to one of said tubes, a stop cock in the stem nearest the first mentioned cock, the lower end of this stem being open to the atmosphere, a measuring vessel having its top connected to the other stem, a stop cock in said first mentioned tube at each side of the stem connected to the vessel, a vertically adjustable liquid reservoir, a flexible tube connecting the reservoir to a stem at the bottom of the vessel and a stop cock in the last mentioned stem.
- at the bottom of the vessel and a stop cock in the last mentioned stem.
7. A gas measuring apparatus including in combination, a horizontal tube having a stop cock at one end adapted to control the supply of gas to the apparatus and an inverted U portion at the other end, said tube also having a downwardly extending stem near said cock, and a second stem between the first stem and the U portion, a stop cock in said first stem the lower end being open to atmosphere, a stop cock at each side of said second stem, a vertical measuring vessel having its top connected to said second stem, a vertically adjustable liquid reservoir, a flexible tube connecting the reservoir to a stem at the bottom of the vessel, and a stop cock in the last mentioned stem.
- 10 8. A gas measuring apparatus including in combination, a horizontal tube having a stop cock at one end adapted to control the supply of gas to the apparatus and an inverted U portion at the other end, said tube also having a downwardly extending stem near said cock and a second stem between the first stem and the U portion, a stop cock in said first stem the lower end being open to atmosphere, a stop cock at each side of said second stem, a vertical measuring vessel having its top connected to said second stem, the above mentioned parts being mounted on a vertical board supported on a horizontal pivot, and means for locking the board in any one of a plurality of angular positions on said pivot.
- 15 9. A gas measuring apparatus including in combination, a horizontal tube having in order from left to right an inverted U portion, a stop cock, a downwardly extending stem, a stop cock, a second downwardly extending stem having a stop cock and its lower end being open to atmosphere, a stop cock adapted to connect the sections of the tube on either side thereof or place the right hand section in communication with the atmosphere, a third downwardly extending stem, the right hand end of the horizontal tube having communication with a gas supply, said third stem having a stop cock and an inclined manometer connected to its lower end, a vertical measuring vessel connected at its top to said first stem, all the above mentioned parts being mounted on a vertical board, a vertically adjustable liquid reservoir, a flexible tube connecting the reservoir to a stem at the bottom of the said vessel, and a stop cock in this latter stem.
- 20 10. A gas measuring apparatus including in combination, a support mounted to tilt about a horizontal axis; and having secured thereto a measuring vessel, a gas supply tube and a gas discharge tube connected to said vessel; and means for locking said support in any one of a plurality of angular positions.

11. A gas measuring apparatus including in combination, a measuring vessel, a gas supply tube and a gas discharge tube connected to the upper end of said vessel, a pivoted support for said parts, and a vertically adjustable liquid reservoir connected to the lower end of said vessel.

12. In apparatus of the class described a backing board, having a vertically adjustable liquid reservoir, a front board pivoted to said backing board, said front board having gas measuring means secured thereto

including a measuring vessel; and means connecting the lower end of said vessel to said reservoir.

13. In apparatus of the class described, a vertically adjustable liquid reservoir, a support pivoted to tilt about a horizontal axis, gas measuring means secured to said support; and a flexible tube connecting said reservoir and measuring means.

In testimony whereof I affix my signature.

HARVEY V. HIGLEY.
